PLUG FUSE AND ADAPTER

George R. Brown, Stratford, Conn., assignor to
General Electric Company, a corporation of
New York

Application October 27, 1934, Serial No. 750,254

7 Claims. (Cl. 200—119)

The present invention relates to fuses and especially to plug fuses provided with adapters for use in the common type of limited circuits.

The object of the invention is to provide a fuse and adapter for use in a fuse socket of the kind in common use, which cannot be shorted through the use of tinfoil, a coin, or other conducting member. The practice of shorting around an ordinary fuse when the fuse burns out is dangerous as it eliminates any protection in a limited circuit and permits the line to be heavily overloaded. The overloading of a line may result in serious trouble at unexpected points in the event of a breakdown and short circuit.

15 In the drawing, Fig. 1 is a sectional view showing an embodiment of the invention; Fig. 2 is an exploded view of Fig. 1; Fig. 3 is a detail sectional view on line 3—3 of Fig. 2; and Fig. 4 shows a modification.

20 Referring to the drawing, 1 indicates a typical fuse socket comprising a casing 2 of insulating material in which is contained a metal screw shell 3. A terminal post 4 passes through the bottom of the casing 2 and is separated from the shell by an insulating washer 5. This is to be taken as typical of any suitable fuse socket.

The fuse comprises a housing 6 made of insulating material, having a base 7 and a side wall 8.

30 A pin 9 which serves as one of the terminals of the fuse passes through an opening 10 in the bottom wall of the base 7. The pin 9 is encircled by a flange 11 which rests against a shoulder 12. The upper end of the pin 9 is peened over as indicated at 13. This holds the pin 9 firmly in place. Extending downward from the base and formed integral therewith is a flange 14 which surrounds the flange 11. The lower end of the pin 9 is threaded. A fuse wire 15 is fastened to the upper end of the pin 9 by a drop of solder 16. The wire 15 extends from the upper end of the pin to the outside of the housing and fits in a groove 17 which extends down the outside of the housing wall 8.

45 Fitted over the housing 6 and holding the fuse wire 15 in place in the groove 17 is an outside casing 18. The casing 18 is of a metallic material and serves as the second terminal. The upper end of the casing 18 is fastened in a non-metallic cover ring 19. A transparent window 20 lies between the upper end of the housing 6 and the cover ring 19. The lower end of the casing is spun over the lower end of the housing 6 as indicated at 21. This holds the casing 18,

window 20, the fuse wire 15 and the cover ring 19 all firmly in position.

The adapter 22 comprises a screw shell 23 which is threaded to screw into the fuse socket shell 3. Formed integral with the bottom of the side wall of the screw shell 23 is an inwardly extending flange 24. Contained in screw shell 23 are four equally spaced spring contacts 25. The outside surface of the contacts 25 engages the inside surface of the screw shell 23. 10 Each contact 25 is formed integral with a ring 26a which fits inside the shell 23 and is in contact with said shell. An inwardly extending flange 26 is formed integral with the ring 26a and rests on the flange 24. The upper portion 15 of the contacts 25 are sprung inwardly as indicated at 27.

A disk 28 made of insulating material is fitted in the bottom of the shell 23 below the inwardly sprung sections 27 of the contacts 25, and rests 20 on the flange 26. The disk 28 reinforces the ring 26a helping to keep the ring in firm engagement with the shell 23. A concentric shoulder 29 extends upward from the top of the disk 28, and surrounds the flange 14 of the fuse. This 25 forms a close fitting, overlapping, horizontal joint between the insulated portion of the plug and the fuse. A threaded opening 30 adapted to receive the pin 9 of the fuse extends through the center of the disk. A metal ring 31 is moulded 30 in the opening 30 of the disk to strengthen the threads of the disk.

A steel spring 32 is fastened in a recess 33 of the disk 28. The end of the spring is pronged and extends through an opening 33a in the screw shell 23. The spring is reinforced by moulded material to prevent flexing in a clockwise direction. The steel spring 32 slopes in a direction such that the adapter may be threaded into a fuse socket. If an attempt is made to unscrew 40 the adapter from the fuse socket, the prongs of the spring bite into the shell and prevent its removal. Spring 32 thus serves as a lock to fasten the adapter in the fuse socket.

When a fuse and adapter as heretofore described are to be installed in a fuse socket for the first time, the pin 9 of the fuse is screwed into the opening 30 of the adapter. As the fuse is drawn down into the adapter, the casing 18 of the fuse engages the inwardly sprung portion 50 of the contacts 25 and a firm contact is made between the adapter and the fuse. The combined fuse and adapter is then threaded into the shell 3 of the standard fuse socket. The adapter, once it is screwed into the fuse socket, cannot be re- 55

moved due to the pronged steel spring which bites into the fuse socket shell. When the fuse is blown due to an overload, the blown fuse is screwed out of the adapter. A new fuse is then threaded into the adapter and the line is again ready for use with the proper protection.

As was stated above, the practice of shorting around a fuse is a dangerous one. The usual procedure for shorting around a fuse, when the fuse blows out, is to remove the fuse, and insert into the fuse socket a coin, metal disk or other conducting material which will make a connection between the center contact and the outer shell of the fuse socket, and then replace the fuse to hold the connector in place. The circuit is then again completed but it is without protection from overloads. Many fires and serious accidents have resulted from this practice. The majority of people are ignorant of the dangers involved in shorting a fuse.

By the use of the adapter and fuse herein described, the shorting of a fuse is prevented. The middle contact of the fuse is the pin 9. In order for the pin 9 to engage the corresponding contact on the shell, it is necessary for the pin of the fuse to be threaded snugly into the insulated washer 28. When in this position, the insulating flange 14 of the fuse fits into the insulated shoulder 29 of the disk 28. Obviously, a metal disk cannot be used to short the fuse as it cannot reach the center contact and the fuse cannot be retained in place as the coin or other metal object would cover the threaded opening. The use of a metal washer having a hole in the center through which the pin would fit is also thwarted due to the overlapping of the flange 14 and the shoulder 29. It would be impossible to screw pin 9 in far enough to make contact with part 4 with a washer lying on shoulder 29. If the attempt were made to use a flexible metal like tinfoil, it would fail because when the flange 14 is screwed down inside shoulder 29, it would pull the tinfoil away from contact with the pin and thus prevent shorting. The pin 9 is made to thread into the hole 30 of the disk 28 with a tight enough fit that it would prevent any conductor being slipped down alongside of the pin.

The modification shown in Fig. 4 of the drawing is a fuse socket in which a fuse plug will fit without the use of a separate adapter. The socket comprises a base 34 in the center of which is an upwardly extending projection 35. In the center of the projection is an opening 36 which is reinforced by a metal ring 37. The ring is spaced from the ends of the opening. Resting on the base and surrounding the projection 35 is a metal ring 38 from the outer circumference of which extends spring contacts 39 at right angles to the ring. The ring is held firmly in place by a metallic bar 40 which has a horse shoe shaped end that fits around the projection and rests on the ring. Opposite sides of the horse shoe section are suitably fastened to the base. The outer end of the bar holds a binding screw 41. Extending across the bottom of the base and covering the opening 36 is a second metal bar 42. The bar extends upward through the base to the top side. A binding post 43 is held by the portion of the bar at the top side. The bar is held in place by rivets 44.

Adapted to fit around the spring contacts 39 is a guard 45 which rests on the base and is held in place by a plurality of screws, one of which is shown at 46. The guard is provided with slots, the walls of which fit around the binding posts

41 and 43 protecting them from outside contact. When placing the socket in use, the lines are fastened to the binding posts before the guard is put in place. After the lines are in place, the guard is fastened down to the base and the socket is complete. The socket functions similarly to the adapter described above in preventing short circuiting around fuses.

The construction has the advantage that it is adapted to fit the fuse sockets now in common use without alteration of the fuse sockets and can be installed by anyone without difficulty. Also it is simple in construction and inexpensive to manufacture. The plug lends itself readily to automatic assembly as all parts are entered and secured from one end. When completely assembled, the plug has no exposed and unsupported edges which can become dented and prevent good contact in the socket.

An important feature of the invention is the arrangement of the spring contacts 25 which engage the casing 18 of the fuse. The lower ends of the contacts are held firmly against the outer shell 23 by the disk 28. The upper portions spring inward as indicated at 27, and when the fuse is screwed in place, contact the outside shell of the fuse firmly, giving a good contact. As these spring contacts are inside of the fuse socket, they are not likely to become bent. Also, since the outer portion of the fuse is the metal casing 18, it is not likely to become bent or damaged in handling. As a result, the fuse will always make proper contact with spring contacts 25 when screwed into place.

What I claim as new and desire to secure by Letters Patent of the United States is:

1. The combination with a fuse socket having two terminals, of an adapter comprising an outer shell which is in contact with one terminal of the fuse socket, a non-metallic disk positioned in said shell having an opening through its center, vertically extending contact means held between the disk and the outer shell, and means for locking said adapter in the fuse socket, and a fuse comprising an outer shell which is in contact with the vertically extending contact means of the adapter, a pin which passes through the opening in the non-metallic disk and is in contact with the second terminal of the fuse socket, and fuse means connecting said pin and said outer shell.

2. The combination with a fuse socket having two terminals, of an adapter comprising an outer shell which is in contact with one terminal of the fuse socket, a non-metallic disk positioned in said shell having a threaded opening in its center, a metallic reinforcing ring in said opening in spaced relation to the surface of said disk, vertically extending contact means held between the disk and the outer shell and means for locking said adapter in the fuse socket, and a fuse comprising an outer shell which is in contact with the vertically extending contact means of the adapter, a threaded pin which screws into the threaded opening in the disk of the adapter and is in contact with the second terminal of the fuse socket, and fuse means connecting the pin and the shell.

3. A fuse adapter comprising a base of insulating material having a central opening for the passage of a fuse pin, a screw shell carried by the base, and spring contact fingers projecting upwardly from the base inside said screw shell.

4. A fuse receiving member comprising a base of insulating material having a central opening for the passage of a fuse pin, an outside wall

carried by the base, and spring contact fingers projecting upwardly from the base inside said outside wall.

5. A fuse socket comprising a base having an opening in its center adapted to receive a fuse pin, spring contacts extending upward from said base spaced equidistant from the opening, and a guard wall adapted to fit around the spring contacts.

10 6. A fuse socket comprising a base having an upwardly extending portion in its center which contains an opening, a contact bar adapted to cover the bottom of said opening, a metallic ring

which surrounds said upwardly extending portion, spring contacts projecting upward from said ring, a second metallic contact bar which holds the ring in place, and a guard surrounding the spring contacts and having slots, the walls of which fit around the ends of the contact bars.

7. A fuse receiving member comprising a base of insulating material having a reinforced opening in its center, an upwardly extending portion surrounding said opening, spring contacts extending upwardly from the base, and an outside wall surrounding said contacts.

GEORGE R. BROWN.
